2,598,527

WATCH ROLLER JEWEL SETTER

Martin J. Freeman, Washington, D. C.

Application April 1, 1947, Serial No. 738,682

10 Claims. (Cl. 81—8)

1

This invention relates to tools for use by watch makers and watch repair men, and more particularly, has reference to a device whereby a roller jewel may be readily positioned in the opening formed in a roller table of a watch.

By way of background, it is pointed out that the roller table of a watch is only a very small component part of the works thereof. Especially is this so in most watches presently in use, it being well known that the tendency is to make watches as flat and as small as possible, with the result that the various parts thereof are exceedingly tiny, and are compressed into a very small area.

In this connection, each roller table is formed with a small opening in which is received a roller jewel. It is necessary to insert the jewel in the opening and to retain it therein, and then to apply cement, the final step of the operation being the application of heat thereto, whereby the cement acts to firmly retain the jewel in the opening. At present, the method customarily employed by watch repair men in performing the necessary setting and cementing operations is to use tweezers or the like to hold the jewel, and then insert the jewel into the opening in the roller table.

This method is unusually time consuming, as will readily be apparent when the size of the roller table jewel opening and the jewel to be fitted thereinto is considered. Additionally, it is often difficult to hold the hand steady during the operation, and sometimes the size of the parts is so small that they must be held close to the jeweler's loop, so close in fact that it becomes difficult to provide sufficient space in which to perform the operation.

The primary object of the invention, therefore, is to provide a device whereby a roller jewel may be set without resort to the troublesome and time-consuming method now required to be employed. It is proposed to attain this object by means of a device in which the roller table may be firmly clamped in a specially proportioned vise, and wherein a jewel may be moved slidably through the opening in the roller table.

A further important object of the invention is to provide a device of the character described which will be relatively inexpensive in construction, whereby the cost of the device will in a comparatively short period of time be fully balanced by savings resulting from the ability of the user to conserve time in the setting operation. This is especially important where a large volume of repair work is handled.

2

Still another important object of the invention is to provide a device of this character that is relatively small in size, comprising a minimum number of parts simply arranged, this being an especially desirable feature in the art, where an already large number of small tools are now in use, it being undesirable to have a tool comprising a large number of easily misplaced parts.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings:

Figure 1 is a top plan view of a jewel setting device constructed in accordance with the invention, one form of roller table being shown mounted thereon, portions of the device being broken away.

Figure 2 is a side elevational view, portions being broken away.

Figure 3 is a view taken substantially on line 3—3 of Figure 1.

Figure 4 is a view taken substantially on line 4—4 of Figure 1.

Figure 5 is a view taken substantially on line 5—5 of Figure 1, and including a longitudinal sectional view through the handle of a vise member.

Figure 6 is an elevational view of a push rod embodied in the invention.

Figure 7 is an elevational view of an aligning needle embodied in the invention.

Figure 8 is a perspective view of the vise member, the handle portion being broken away.

Referring to the drawing in detail, the reference character 5 designates a base. This is preferably formed of metallic material, and may be hollowed, as shown in Figure 5. The base may be of any suitable conformation, it being necessary only that it present a steady support for the operation.

The base has a flat upper surface 6, and from one end thereof there is upwardly extended a wall 7. This may conveniently be cast integral with the base, and has flat side surfaces that are disposed perpendicularly to the upper surface 6 of the base 5.

At one end, the wall 7 is cut away as at 8, the cutaway portion being relatively deep, so as to present a comparatively wide and deep open

space at one side of the device, the purpose of which will be described in detail hereinafter.

As best shown in Figure 5, the wall 7 is further formed with a transverse bore 9 that is parallel to the plane of the flat upper surface 6 of the base. The bore 9 is disposed substantially centrally, relative to the upper and lower edges of the wall 7.

Fitted tightly into the bore 9, so as to be immovably held therein, is a relatively elongated tubular member 10. One end, designated by the reference character 11, is flush with the inner side surface of the wall 7, as best shown in Figure 5. From the end 11, the tubular member 10 is extended laterally away from the wall 7. The tubular member 10 is formed with an end-to-end bore 12, that is open both at the end 11, and at the free end 13 of the tubular member. In diameter, the bore 12 is relatively small, corresponding substantially to the diameter of a roller jewel J that is slidably therethrough. In this connection, roller jewels are, in general, cylindrical or semi-cylindrical. It is essential only that the bore 12 be of such diameter as will permit a roller jewel J to be slidably moved therethrough, without substantial deviation from its path of movement.

Referring to Figure 7, an aligning needle 14 is illustrated that may be inserted in the free end 13 of the tubular member 10, this needle being of such length as will result in its pointed end projecting from the other end 11 of the tubular member when it has been inserted therein.

Alternative to the aligning needle 14, a push rod 15 is also adapted to be inserted in the free end 13 of the tubular member 10. The push rod 15, as clearly shown in Figure 6, is cylindrical in form, the diameter thereof corresponding substantially to the diameter of the bore 12 of the tubular member. The push rod 15 is provided with the collar 16. Referring particularly to Figures 1 and 2, the push rod is there shown inserted to the maximum extent possible in the bore 12. It is observed when it has been so inserted, the collar 16 engages the free end 13 of the tubular member 10. When these parts are so engaged, the other end of the push rod 15 projects barely beyond the inner side surface of the wall 7, that is, it moves fully up to, but does not enter, the jewel-receiving opening in a roller table R mounted in close spaced relation to said inner side surface of the wall 7. This construction is particularly shown in Figure 5.

Intermediate its ends, the tubular member 10 is provided with a cutaway part 17, whereby a portion of the bore 12 is exposed. As a result, an open groove is provided that is aligned axially with the bore 12. This permits a jewel J to be placed in the channel or bore 12, preliminary to being moved therethrough by means of the push rod 15.

At the other end of the base 5, a rear wall 18 is provided, that extends perpendicularly from the flat upper surface 6 of the base 5. This may obviously be cast integral with the base 5 if desired.

Adjacent the lower edge of the rear wall 18, and formed parallel thereto, is provided a horizontal slot 19 that extends inwardly from one end of the wall. At the inner end of this horizontal slot, and in communication therewith, is a vertical bore 20, that is threaded to receive a set screw 21. The set screw 21 has an enlarged head 22 which engages the upper edge of the rear wall 18 when the set screw is fully threaded into the bore

20. The head 22 may be knurled as illustrated, and it is preferably additionally formed with handles 23. Thus, the knurled portion may be used for primary adjustment of the set screw, while the handles 23 are operable for making more minute adjustments.

Adjacent the open end of the horizontal slot 19 the lower end of a vertical threaded bore 24 is in communication therewith, the bore 24 receiving the set screw 25. A small screw 26 is additionally threadable through the wall 18, and is adapted to close the open end of the slot 19.

The slot 19 is proportioned to receive a vise for holding the roller table R. A handle 27 is formed with an end-to-end bore, that is threaded at one end to receive the threaded end of a tubular member 28, that constitutes the shank of the vise. The other end of the tubular member 28 is provided with a stationary or rear jaw 29, which, as clearly shown in Figure 8, is formed integrally with a laterally extended extension member 30, which is formed of a heat-conductive material.

Slidable in the tubular member 28 is a rod 31, having at one end a thin flat movable jaw 32. The upper edge of the jaw 32 extends slightly above the upper surface of the rear jaw 29, and is formed with one or more semicircular notches 33.

At the other end of the rod 31 there is slidably positioned thereover a small cylindrical block 34, the threaded end of the rod 31 projecting beyond said block and beyond the handle 27. A regulating stud 35 is threaded onto the projecting end. Thus, it is seen that threading of the stud 35 on the rod 31 to a desired extent, so as to adjust the distance between the cap of the stud and the adjacent end of the handle 27, will in turn adjust the distance that the jaws 29 and 32 of the vise can be spread apart.

A spring 36 is interposed between the block 34 and the rear end of the tubular member 28, so that after the jaws 29 and 32 are spread apart by pressure applied to the end or cap of the regulating stud 35 the movable jaw 32 is returned to normal position under expanding action of the spring 36.

A pin 37 extends rearwardly from the movable jaw 32 through an opening in the jaw 29, whereby to hold the jaws in proper alignment at all times.

Other than the particular jaw formation described herein, vises of this type are known in the art, the description provided herein being submitted for the purpose of explaining the operation of the vise as used in conjunction with the remainder of the device.

In operation of my device, the roller table R, which may be of either double type, as illustrated, or the single type, is placed between the jaws of the vise. In the drawings, the roller table has been enlarged considerably, above the proportion which it would ordinarily bear to the device which constitutes the invention, this having been done for the purpose of illustrating more clearly the operation of the device.

In mounting the roller table in the jaws of the vise, the roller table is positioned so that its jewel receiving opening is brought into alignment, as far as possible, with one of the notches 33 in the jaw 32. The lower half of the jewel opening in the roller table R thus constitutes in effect an extension of the semi-circular wall of the notch.

The vise is then manually moved forwardly, so that the outer face of the jaw 32 engages the rear face of the wall 7. At the same time, the

operator brings the jewel opening in the roller table R into rough axial alignment with the open end of the bore 12.

The needle 14 is then inserted into the other end 13 of the bore 12 and is extended through the jewel opening in the roller table R. Thus, the jewel opening is immediately and accurately brought into full register with the adjacent end of the bore 12.

Obviously, this operation can be performed somewhat differently, if desired. The operation may be begun by inserting the aligning needle 14 through the bore 12 so as to project therebeyond. Then, the vise having the roller table R mounted therein in the manner previously described, may be moved forwardly so that the end of the needle is received in the jewel opening.

Preferably with the needle 14 still extended through the jewel opening in the roller table R, so that the opening and the bore 12 are not accidentally moved out of register, the set screw 21 is operated to clamp the vise in position.

The aligning needle 14 is then removed, and a jewel J is deposited in the groove formed by the cutaway portion 17 of the tubular member 10. The push rod 15 is then inserted, and is used to push the jewel J through the bore 12, across the notch 33, and into the jewel opening in the roller table R. As previously described, the length of the push rod 15 is such that it moves only up to the nearest face of the roller table R when the collar 16 engages the end 13 of the tubular member 10.

As a result of this construction, it is to be observed that the rear end of the jewel J, that is the end positioned in the jewel opening of the roller table, will be exactly flush with the face of the roller table R after the push rod 15 is withdrawn. It is thus placed in proper position for the necessary cementing operation.

The jewel having been set, the set screw 21 is threaded out of engagement with the shank 28 of the vise, and the vise is slidably moved toward the open end of the slot 19. The vise is positioned below the set screw 25, which is threaded against the vise to clamp it in position again.

In this position, the extension 30 of the jaw 29 projects laterally beyond the base 5, and the jewel J, positioned in the jewel opening of the roller table, is exposed for cementing operations by provision of the cutaway portion 8 of the wall 7. Cement is applied, whereupon a jeweler's lamp or the like is positioned to apply heat to the extension 30. The application of the heat results in a completion of the mounting of the jewel in the roller table.

The small screw 26 cooperates with the set screw 25, to hold the vise in proper position for the cementing and heating steps. By threading of the screw 26 to close the slot 19, all possibility of the vise slipping out of the slot is removed.

The advantages of a device constructed in accordance with the invention are believed to be obvious, and need not be dwelt upon other than to state that the device removes the necessity of setting a roller jewel by means of the time-consuming and troublesome method now employed.

What is claimed is:

1. A roller jewel setting device comprising a base, a wall thereon, a tubular member formed with an end-to-end bore and having one end extended through the wall, the tubular member having a jewel-receiving cutaway part communicating with the bore, a push rod slidable in

the bore, a vise-holding means on the base, and a vise including jaws one of which has a notch, said vise being mounted on the base in a position wherein said notch is in line with the bore.

5. A roller jewel setting device comprising a base, a wall at one end thereof, a tubular member formed with a jewel-receiving bore and having one end fixedly mounted in the wall, means for moving a roller jewel through said end, a wall 10 at the other end of the base formed with a slot extended from one edge thereof, and a vise having a shank mounted in the slot, the vise including jaws one of which has a notch, said vise being movable into a position in which the notch is 15 in line with the bore.

3. A roller jewel setting device comprising a base, an upstanding wall mounted thereon, a tubular member formed with an end-to-end bore and having one end fixedly mounted in the wall, 20 the tubular member being extended laterally from the wall, the wall of the tubular member being partially cut away to form a jewel-receiving groove axially aligned with the bore, vise holding means mounted on the base and spaced from the wall, a vise mounted on said means and including jaws for holding a roller table, one of the jaws having a notch alignable with the jewel receiving opening of a roller table, means for mounting the vise in positions of adjustment, 25 said positions including one in which said notch and opening are in registry with the bore, and means extending through the bore of the tubular member for moving a roller jewel through the bore and across the notch into the jewel opening 35 formed in the roller table.

4. A roller jewel setting device comprising a base having a flat upper surface, a fixed member thereon having a jewel-receiving bore parallel to said upper surface, a vise mounted on the base 40 for holding a roller table thereon with its jewel opening aligned with the bore, said vise including jaws and having one of its jaws formed with a notch in its upper edge, the vise being adjustable to a position in which said notch will register with and comprise an extension of the bore, the vise having a flat lower edge engaging the upper surface of the base, and means for moving a jewel through the bore and notch and into said jewel opening.

5. A roller jewel setting device, comprising a base, a member having a bore fixedly mounted thereon, a push rod slidable in the bore, whereby to move a roller jewel therethrough, a vise including jaws for gripping a roller table and one of the jaws having a notch, means for adjustably mounting the vise on the base in positions in one of which the notch registers with and comprises an extension of the bore, and a heat-conductive extension on one of the jaws of the vise.

6. A roller jewel setting device comprising a base, a stationary member thereon having a bore, vise jaws mounted on the base for positioning against said member and adapted for gripping a roller table having a jewel opening, one of said jaws having a notch, an aligning needle extending through the bore, notch, and jewel opening to bring them into register, and means for clamping the jaws to the base in the position in which registry occurs, for movement of a jewel through the bore and across the notch into the jewel opening.

7. A roller jewel setting device comprising a base, an abutment extended upwardly from the base and there being a bore extending through the abutment, a vise mounted on the base for

7 movement against the abutment, said vise including jaws adapted to grip between them a roller table having a jewel opening and one of said jaws having a notch, an aligning needle extending through the bore, notch, and jewel opening to bring them into register, and means for clamping the vise to the base in the position in which registry occurs, for movement of a jewel through the bore and across the notch into the jewel opening.

8. A roller jewel setting device comprising a base, an abutment extended upwardly from the base and there being a bore extending through the abutment, a second abutment extended upwardly from the base and spaced from the first abutment, a vise movably supported by the second abutment for movement against the first abutment, said vise including jaws adapted to grip between them a roller table having a jewel opening and one of said jaws having a notch, an aligning needle extending through the bore, notch, and jewel opening to bring them into register, and means for clamping the vise to the second abutment in the position in which registry occurs, for movement of a jewel through the bore and across the notch into the jewel opening.

9. A roller jewel setting device comprising a base, an abutment extended upwardly from the base and there being a bore extending through the abutment, a second abutment upstanding from the base and spaced from the first abutment, said second abutment having a lateral slot, a vise mounted for movement in the slot and against the first abutment, said vise including jaws adapted to grip between them a roller table having a jewel opening, one jaw being nearer the first abutment than the other jaw and being formed with a notch, an aligning needle extending through the bore, notch, and jewel opening to bring them into register, and a set screw extending through the second abutment for clamp-

ing the vise to the second abutment in the position in which registry occurs, for movement of a jewel through the bore and across the notch into the jewel opening.

10. A roller jewel setting device comprising a base, an abutment upstanding from the base, said abutment having a bore, a second abutment upstanding from the base and spaced from the first abutment, the second abutment having a lateral slot, a vise movably mounted in the slot and including jaws adapted for gripping a roller table having a jewel opening between them, said vise being movable up against the first abutment, one jaw being nearer the first abutment than the other jaw and being formed with a notch, an aligning needle extending through the bore, notch, and jewel opening to bring them into register, and a set screw threaded in the second abutment for clamping the vise to the second abutment in the position in which registry occurs for movement of a jewel through the bore and across the notch into the jewel opening, there being a heat conductive lateral extension integrally formed on one of the jaws, the first abutment having one side partially cut away to expose the roller table and a jewel set therein on lateral movement of the vise to said cut-away side, for application of heat to the extension to cement the jewel.
